(57)

CLAIM

The ornamental design for a reagent bottle, as shown and described.

DESCRIPTION

FIG. 1 is a front perspective view of the design.

FIG. 2 is a front view thereof.

FIG. 3 is a back view thereof.

FIG. 4 is a left side view thereof.

FIG. 5 is a right side view thereof.

FIG. 6 is a top plan view thereof; and,

FIG. 7 is a bottom plan view thereof.
